UNITED STATES PATENT OFFICE.

ALLEN A. TIRRILL, OF PITTSBURGH, PENNSYLVANIA, ASSIGNOR TO WESTINGHOUSE ELECTRIC & MANUFACTURING COMPANY, A CORPORATION OF PENNSYLVANIA.

REGULATING SYSTEM.

1,396,898.

Specification of Letters Patent.

Patented Nov. 15, 1921.

Application filed September 19, 1918. Serial No. 254,760.

To all whom it may concern:

Be it known that I, ALLEN A. TIRRILL, a citizen of the United States, and a resident of Pittsburgh, in the county of Allegheny and State of Pennsylvania, have invented a new and useful Improvement in Regulating Systems, of which the following is a specification.

My invention relates to electrical regulating systems and particularly to electric regulators of the vibrating-contact type.

One object of my invention is to provide a regulating system of the above-indicated character that shall respond quickly, and with substantially no time lag, to any voltage variation in a supply circuit and be substantially free from the contact troubles which are frequently encountered in regulators of the vibrating-contact type.

In regulators of the vibrating-contact type, it is customary to provide a very sensitive main control element that is operated in accordance with the voltage obtaining in the supply circuit. A differential relay, that is governed by the main control element, is adapted, in turn, to govern the operation of the main control element and of an exciter generator which regulates the voltage of the main generator that is connected to the supply circuit. It is very desirable, in regulators of this type, that the differential relay be quick acting and be operated in a manner to prevent excessive contact trouble in the main control element.

According to my invention, resistors are severally connected in series with the windings of the differential relay for increasing the speed of the relay, and resistors are severally connected in shunt to the windings of the differential relay in a manner to prevent excessive contact trouble in the main control element.

In the accompanying drawing, Figure 1 is a diagrammatic view of a regulator system constructed in accordance with my invention, and Fig. 2 is a diagrammatic view of the circuits completed through the windings of the differential relay.

Referring to the drawing, a generator 1, comprising an armature 2 and a field winding 3, is connected across a supply circuit comprising conductors 4, 5 and 6. The field winding 3 of the generator is connected, through an adjustable resistor 8, to an aux-

iliary exciting generator 7. The exciting generator 7 comprises an armature 9 and a shunt field winding 10 that is connected in circuit with an adjustable resistor 11.

A regulator, comprising a main control element 12 and a differential relay 13, is employed for short-circuiting the resistor 11, under predetermined conditions, to regulate the voltage of the generator 1.

The main control element 12 comprises a resiliently mounted contact member 14 and a co-operating contact member 15 that is mounted upon a lever 16. The lever 16 is pivotally mounted upon a bell-crank lever 17. A counterweight 18 is attached to one end of the lever 16, and a solenoid core 19, that is controlled by a winding 20, is attached to the opposite end of the lever. The winding 20 is connected across the supply conductors 4 and 6 by means of a transformer 21 and thus effects operation of the contact members 14 and 15 in accordance with the voltage obtaining in the supply circuit.

A winding 22, that is intermittently connected to the transformer 21 in a manner to be hereinafter set forth, operates upon a core member 23 that is pivotally attached to the bell-crank lever 17 near one end thereof, for the purpose of effecting vibration of the contact member 15. The core members 19 and 23 are respectively provided with dash-pots 24 and 25 for retarding their movements, and a retractile spring 26 is connected to the bell-crank lever 17 for counterbalancing a portion of the weight of the core 23.

The differential relay 13 comprises two pairs of differential windings 27 and 28 and an armature 29 that is retracted by means of a spring 30, when the two windings 27 and 28 are simultaneously energized, for effecting engagement of the contact members 31 and 32. The winding 28 is constantly energized by a battery 33 through a circuit including substantially non-inductive resistors 34 and 35. The winding 27 is intermittently connected to the battery 33, through substantially non-inductive resistors 36 and 35, by means of the contact members 14 and 15. Two resistors 37 and 38 are respectively provided for shunting the windings 27 and 28 in order to prevent excessive burning and wear of the contact members 14 and 15 due to the inductance of the differential relay windings. The contact members 31 and 32

of the differential relay serve to govern the operation of two auxiliary relays 39 and 40, which may be of any desired type or kind, the relay 39 serving to short-circuit a portion 5 of the resistor 41 for effecting intermittent operation of the main-contact relay by means of the coil 22, and the relay 40 serving to short-circuit the resistor 11 which governs the excitation of the exciter 7 and, consequently, the voltage of the main generator 1.

Assuming the system to be in the condition illustrated in the drawing and the voltage of the supply circuit to be suddenly lowered; the energization of the winding 15 20, which is connected across the supply conductors 4 and 6 by means of the transformer 21, is reduced to permit engagement of the contact members 14 and 15. Upon engagement of the contact members 14 and 15, a 20 circuit is completed from the battery 33 through the resistors 35 and 36 and the winding 27 to effect simultaneous energization of the two differential windings 27 and 28. The two windings 27 and 28 neutralize 25 the action of each other and permit engagement of the contact members 31 and 32 to effect operation of the relays 39 and 40. The relay 40, as hereinbefore set forth, short-circuits the resistor 11 and, accordingly, increases the excitation of the exciter 7 and the voltage of the generator 1. The relay 39 short-circuits a portion of the resistor 41 which is included in the circuit 30 of the winding 22. Consequently, the energization of the winding 22 is increased 35 to raise the core armature 23, thereby operating the levers 17 and 16 to effect disengagement of the contact members 14 and 15. The contact members 14 and 15 may again 40 be brought into engagement with each other and the intermittent vibration of the contact member 15 be continued, as described for regulating the voltage of the supply circuit.

The employment of the resistors 34 and 45 36 in series with the differential windings 28 and 27 effects a material increase in the speed of operation of the relay but it also causes a correspondingly increased tendency for the contacts of the main control element 50 to stick together. However, I have discovered, by experiment, that, if two equal resistors are connected in shunt to the two differential windings illustrated in Fig. 2 of the drawing, the sticking of the contact 55 members, which is occasioned by increasing

the speed of the relay, is substantially obviated.

Modifications in the system and arrangement and location of parts may be made within the spirit and scope of my invention, 60 and such modifications are intended to be covered by the appended claims.

I claim as my invention:

1. In a regulator, a relay having two differential windings, resistors severally connected in series with, and in shunt to, said windings, and means for opening and closing the circuit of one of said windings. 65

2. In a regulator, a relay having two differential windings, contact members for opening and closing the circuit of one of said windings, resistors severally connected in series with the windings for increasing the speed of the relay, and resistors severally connected in shunt to the windings for preventing sticking of the contact members. 70 75

3. In a regulator, a relay having two differential windings, one of said windings being normally energized, contact members for effecting intermittent energization of 80 the other winding, and resistors connected in shunt to the windings for preventing sticking of the contact members.

4. In a regulator, a relay having two differential windings, means for constantly 85 energizing one of said windings, contact members for effecting intermittent energization of the other winding, resistors severally connected in shunt to the two windings for preventing sticking of the contact members, 90 and resistors severally connected in series with the two windings for increasing the speed of the relay.

5. A regulator comprising a relay having differential windings, means for effecting 95 intermittent energization of one of the windings, resistors respectively in series with the windings, and resistors respectively in permanent shunt circuits to the windings.

6. A regulator comprising a relay having 100 differential windings, means for effecting intermittent energization of one of the windings, substantially non-inductive resistance in series with the windings, and substantially non-inductive resistance permanently 105 in shunt to the windings.

In testimony whereof, I have hereunto subscribed my name this 11th day of Sept., 1918.

ALLEN A. TIRRILL.
